CLAIM

The ornamental design for a thermostat, as shown and described.

DESCRIPTION

FIG. 1 is a bottom plan view of a thermostat showing our new design;

FIG. 2 is a front elevation view thereof;

FIG. 3 is a rear elevation view thereof;

FIG. 4 is a left side elevational view thereof;

FIG. 5 is a right side elevational view thereof;

FIG. 6 is a top plan view thereof;

FIG. 7 is a bottom right perspective view thereof;

FIG. 8 is a bottom rear perspective view thereof;

FIG. 9 is a bottom perspective view thereof;

FIG. 10 is a top right perspective view thereof; and,

FIG. 11 is a top left perspective view thereof.
